COIN ACTUATED CALENDAR BANK

Alfred E. Maage, Jr., Milwaukee, Wis., assignor
to M. A. Gerett Corporation, Milwaukee, Wis.

Application May 10, 1951, Serial No. 15,123

Term of patent 14 years

(Cl. D34—11)

To all whom it may concern:

Be it known that I, Alfred E. Maage Jr., a citizen of the United States, residing at Milwaukee, in the county of Milwaukee and State of Wisconsin, have invented a new, original, and ornamental Design for Coin Actuated Calendar Bank, of which the following is a specification, reference being had to the accompanying drawing, forming a part thereof.

In the drawing:

Figure 1 is a front perspective view of a coin actuated calendar bank, showing my new design;

Figure 2 is a rear perspective view of the coin actuated calendar bank shown in Figure 1; and

Figure 3 is a horizontal sectional view, taken

on the line 3—3 of Figure 1, showing the relationship of the assembled parts of the coin actuated bank.

I claim:

The ornamental design for a coin actuated calendar bank, as shown and described.

ALFRED E. MAAGE, JR.
